(57) **CLAIM**

I claim the ornamental design for a four spouted round bottomed tube, as shown and described.

DESCRIPTION

FIG. 1 is a front view of a four spouted round bottomed tube showing my new design, the rear being the mirror image of thereto;

FIG. 2 is a front view thereof, shown at a slight rotated angle;

FIG. 3 is a top plan view thereof;

FIG. 4 is an across-sectional view thereof, taken along the line 4—4 of FIG. 2;

FIG. 5 is a bottom plan view thereof; and,

FIG. 6 is a front top and left side view thereof.
